CHECK BOOK COVER

Sidney B. Klahn, Portland, Oreg.

Application August 5, 1935, Serial No. 34,646

1 Claim. (Cl. 281—19)

This invention relates generally to book covers, and particularly to a check book cover.

The main object of this invention is the provision of a new form of check book cover in which the cover is made of one piece, which is so shaped and joined as to form a cover which is inexpensive to manufacture and which will effectively hold a pad of check blanks as well as a pass book.

The second object is the construction of a check book cover from which all the seams and board fillers are eliminated for the purpose of producing a durable, neat appearing book which is not cumbersome.

These and other objects are accomplished in the manner set forth in the following specification as illustrated in the accompanying drawing, in which:

Fig. 1 is a plan of the blank from which the book cover is made.

Fig. 2 is an enlarged section taken along the line 2—2 in Fig. 1.

Fig. 3 is a view similar to Fig. 1, but showing the first flap turned down.

Fig. 4 is a view similar to Fig. 3, but showing the side flaps turned in.

Fig. 5 is a section taken along the line 5—5 in Fig. 4.

Fig. 6 is a perspective view showing the closed book.

Similar numbers of reference refer to similar parts throughout the several views.

Referring in detail to the drawing, there is shown in Fig. 1 a blank constituting the front 10, the back 11, which is separated from the front 10 by a crease 12, and a front flap 13, which is separated from the back 11 by a crease 14. From the opposite end of the front 10 extends the pocket flap 15, whose edge 16 is tapered, as shown in Fig. 2.

Side flaps 17 project from opposite sides of the front 10. The pocket flap 15 is provided with cut-out portions 18 which extend to the shoulder 19. The crease 20 between the front 10 and the pocket flap 15 is substantially midway between the shoulder 19 and the edge 21 of its adjacent flap 17. A snap fastener 22 is placed on the rear side of the front 10 and a corresponding fastening unit 23 is placed on the front flap 13.

In assembling this device, the pocket flap 15

is turned in along the crease 20, as shown in Fig. 3, and adhesive is applied to the surface 24 while a gummed strip 25 is placed against the member 15, as shown in Fig. 3, after which the side flaps 17 are brought to the position shown in Fig. 4, causing the edges 26 to be held together while the edges 27 are secured to the surface 24 forming thereby two pockets, the first one between the flap 17 and the pocket flap 15 into which is placed a tongue 28 of the check book 29. The second pocket lies between the pocket flap 15 and the front 10, and it is into this pocket that the pass book 30 may be placed.

It can be seen from the foregoing that by this construction all sewing and board filler is dispensed with, and by the use of a suitable material such as a waterproof composition, both the check book and pass book are fully protected in the neatest possible manner and at a relatively small expense.

While I have thus illustrated and described my invention, it is not my intention to be limited to the precise shape and construction illustrated in the accompanying drawing, but I do intend to cover all such forms and modifications thereof that fall fairly within the appended claim.

I claim:

A check book cover consisting of an elongated strip of flexible material of single thickness, the lateral edges of which are parallel, said strip having transverse creases formed therein dividing the strip successively into a pocket flap, back, front, and front flap sections, the front and back sections being substantially equal in length, said back section having side flaps projecting laterally therefrom, the ends of said side flaps which are adjacent to the pocket flap crease are spaced therefrom, said pocket flap section being offset at each side along that portion of its length extending from its outermost end to a point which is equidistant from the pocket flap crease with the adjacent ends of the side flaps, the side flaps when folded to enclose the offset portion of the pocket flap being adapted to receive means for uniting the outermost ends of said side flaps and means for securing said front flap against the outside of said back.

SIDNEY B. KLAHN.
